US00D800746S

(12) **United States Design Patent** (10) Patent No.: **US D800,746 S**
(45) Date of Patent: **** Oct. 24, 2017**

(54) **DISPLAY SCREEN OR PORTION THEREOF WITH GRAPHICAL USER INTERFACE**

(71) Applicant: **Branch Banking and Trust Company**, Winston-Salem, NC (US)

(72) Inventors: **Michael Anthony Dascola**, Raleigh, NC (US); **Christopher Pearce**, Cary, NC (US); **Matthew T. Spriggs**, Cary, NC (US)

(73) Assignee: **Branch Banking and Trust Company**, Winston-Salem, NC (US)

(**) Term: **15 Years**

(21) Appl. No.: **29/537,340**

(22) Filed: **Aug. 25, 2015**

(51) LOC (10) Cl. **14-04**

(52) U.S. Cl.

USPC **D14/486**

(57) **CLAIM**

The ornamental design for a display screen or portion thereof with graphical user interface, as shown and described.

DESCRIPTION

The sole FIGURE is a front view of a display screen or portion thereof with graphical user interface.

The broken line perimeter illustrates a display screen portion and forms no part of the claimed design.

1 Claim, 1 Drawing Sheet
